gesellschaft, Chemnitz, Germany

Application June 3, 1936, Serial No. 83,362
In Germany July 10, 1935

4 Claims. (Cl. 66—89)

The present invention relates to straight knitting machines equipped with a Jacquard petinet attachment and more particularly to the narrowing device for such machines.

To produce full fashioned stockings upon a straight knitting machine equipped with a Jacquard petinet attachment, several narrowing operations are required. Besides the Jacquard patternings adapted to be produced at any place of the fabric by a narrowing comb extending over the whole width of the division and provided with a narrowing point or tickler needle for each of the frame needles in the division, the narrowings at the shank, the calf, the heel and the toe, and the widening at the heel also must be effected.

For the purpose of avoiding the disadvantages of the use of a one-part narrowing comb which extends over the whole width of the division and allows one-sided narrowing operations to be carried out in one direction only, it is well known to use a two-part narrowing comb also extending over the whole width of the division. In such a divided narrowing device both narrowing combs move in unison and in the same direction during patterning, but perform separate but simultaneous movements in opposite direction for narrowing and widening purposes. Hereby a substantial loss of time caused by producing narrowings or widenings by narrowing and widening operations effected in one direction only is prevented.

This two-part or divided narrowing device has the drawback, that in producing split fabric, the split connection is destroyed or at least strongly endangered by throwing in narrowing points or tickler needles operating above the split connection.

The above mentioned drawback is eliminated by the narrowing device forming the subject matter of the present invention. In a manner well known in the art, the novel narrowing device also extends over the whole width of the division, has a tickler needle or narrowing point for each frame needle in the division and serves for producing patternings as well as narrowings and widenings respectively. In accordance with the invention, however, the narrowing device is subdivided into three parts in such a manner, that a space free of tickler needles or narrowing points may be obtained for producing split connections for instance during knitting of the sole portion.

All three parts of the narrowing device move in unison and in the same direction during patterning, while for narrowing and widening pur-

poses the outer parts of the narrowing device perform separate but simultaneous movements in opposite directions. The middle part of the narrowing device may, during narrowing or widening, be swung inwardly into the operative position 5 for effecting patternings, may, however, also be swung outwardly into an inoperative position.

To allow narrowings and widenings to be effected simultaneously at both sides of the fabric, the two outer parts of the narrowing device are 10 shiftably arranged. The individual parts of the narrowing device are brought into the different operating positions by insertion and withdrawal respectively of special intermediate members. Due to the advantageous subdivision of the narrowing device into three parts, split connections are no longer endangered by working tickler needles or narrowing points as now at the places at which split connections are produced no troubling tickler needles or narrowing points are 15 present. 20

In the accompanying drawings one construction of a narrowing device according to the invention is shown by way of example.

In the drawings:

Fig. 1 is an elevation, partly in section, of the narrowing device showing the individual parts in the patterning position. 25

Fig. 2 is an elevation, partly in section, of the narrowing device in the position adapted for effecting narrowings or widenings, showing the middle part of the narrowing comb in its original position and the lateral parts shifted outwardly into a position necessary for producing, for instance during the manufacture of the sole portion, split connections free of objections in the spaces between the parts of the narrowing device, and 30

Fig. 3 is an elevation, partly in section, of the narrowing device, showing the middle part of the narrowing comb swung outwardly and the lateral parts moved against each other into a position suitable for the manufacture of the toe portion. 35

In suitable bearings 1 and 2 of a straight knitting machine, not shown in the drawings, a bar 3 is rotatably and shiftably mounted upon which two arms 4 and 5 are fixed, carrying the middle portion 6 of a subdivided narrowing comb. Rotatably and shiftably mounted in bearings 7 and 8 of the knitting machine is a further bar 9, 45 while in other bearings 10 and 11 a third bar 12 is rotatably and shiftably arranged. Fixed to the bar 9 are two arms 13 and 14 carrying a lateral portion 15 of the subdivided narrowing comb while two arms 16 and 17, carrying a second lat- 50

55

eral portion 18 of the subdivided narrowing comb, are fixed to the bar 12. The three narrowing portions 6, 15 and 18 form a narrowing comb extending over the whole width of the division. The associated needle bar is shown at 19. The bar 3, carrying the middle portion 6 of the narrowing comb, is permanently drawn against the bearing 1 by a tension spring 20 connected with its ends to the bearing 1 and to a collar 21 respectively which is mounted between two collars 22, 23 fixed upon the bar 3. An adjustable collar 24 fixed upon the bar 3 limits the lateral movement of the latter.

The bar 9, carrying the lateral portion 15 of the narrowing comb, is, by means of a spring 25, permanently drawn against a stop 26 of a slide 27, while the bar 12, carrying the lateral portion 18 of the narrowing comb, is in a similar manner drawn against a stop 28 of a slide 29 by means of a spring 30.

The slide 27 is shiftably arranged upon a rod 31 guided in a bearing 32. The rod 31 bears against a narrowing slide 33 which forms part of the narrowing tackle and is vertically movable in a fixed guide 34. The vertical movement of the slide 33 is effected by a stepped cam 35, shiftably mounted upon the cam shaft 36. The stepped cam 35 is shifted by the arm 37 of a double-armed lever 37, 38, mounted upon a bolt 39 journalled in the frame of the machine. The arm 37 engages an annular groove 40 in a socket 41 of the stepped cam 35. The other arm 38 of the double-armed lever 37, 38 is acted upon by a rod 42. The rod 31 is pressed against the slide 33 by a spring 43 one end of which is connected to the slide 27, while the other end is attached to the bearing 32. Mounted in the slide 27 are two intermediate members 44, 45 which may be adjusted in a direction vertically to the longitudinal axis of the rod 31. The intermediate members 44, 45 are connected to handles 46, 47 and acted upon by springs 48, 49, surrounding the shanks 50, 51 of the handles 46, 47. The springs 48, 49 are located in recesses 52, 53, formed in the slide 27, and their ends bear against the bottom of the recesses 52, 53 and the intermediate members 44, 45 respectively. By shifting the slide 27 upon the bar 31 against the action of the spring 43, the intermediate members 44, 45 may be brought in front of the rod 31, so that the position of the slide 27 upon the rod 31, bearing against the narrowing slide 33, is correspondingly altered. The intermediate members 44, 45 may be withdrawn again by means of the handles 46, 47.

The slide 29 is shiftably arranged upon a rod 54 guided in a bearing 55. The rod 54 bears against a narrowing slide 56 vertically movable in a fixed guide 57. A stepped cam 58 shiftably mounted upon the cam shaft 36 serves to vertically adjust the slide 56. The free end of the arm 59 of a double-armed lever 59, 60, mounted upon a bolt 61 journalled in the frame of the machine, engages an annular groove 62 in a socket 63 of the stepped cam 58 shiftably arranged upon the cam shaft 32. The other arm 60 of the double-armed lever 59, 60 is acted upon by a rod 64. The rod 54 is pressed against the slide 56 by a spring 65, connected with one of its ends to the slide 29 and with its other end to the bearing 55. The slide 29 also carries two intermediate members 66, 67 which may be vertically adjusted with regard to the longitudinal axis of the rod 54. The intermediate members 66, 67 are connected to handles 68, 69 and are acted upon by

springs 70, 71, surrounding the shanks 72, 73 of the handles 68, 69 and located in recesses 74, 75 of the slide 29. One end of each spring 70, 71 bears against the bottom of the corresponding recesses while the other end bears against the associated intermediate member 66, 67 respectively. By this means the position of the slide 29 upon the rod 54 may also be altered.

Carried by one end of the bar 3 is a bracket 76 which for the sake of clearness is shown in all figures in a position turned to about 90° out of its real position. The free end of this bracket 76 carries a pin 83 upon which an intermediate stop member 84 is swingably mounted. The member 84 has a recess 81 in which a spring 80 is located. The latter surrounds a pin 82 and bears against a head or block forming a part thereof for normally pressing the pin 82 against one or the other flattened surfaces 78, 79 of the pin 83.

In the position of the individual parts shown in Fig. 1, the intermediate stop member is swung downwardly. The three parts 18, 6 and 15 of the narrowing device form a narrowing comb, so that patternings may be made in a well known manner.

In the slide 27 the intermediate member 45 is brought in front of the rod 31 and in the slide 29 the intermediate member 67 is brought in front of the rod 54, so that the stops 26 and 28 occupy a position in which by the bars 9 and 12 bearing against the stops 26 and 28 respectively, the lateral parts 15 and 18 of the narrowing device are shifted against the middle part 6.

By shifting the rods 42 and 64 in the direction of the arrows or vice versa, the stepped cams 35 and 58 respectively may be adjusted to raise or lower the slides 33 and 56. Due to this movement the rods 31 and 54 respectively, bearing against the slides 33 and 56 respectively and thereby the slides 27 and 29 respectively are laterally shifted. By the bar 9, bearing against the stop 26 of the slide 27, the bar 3 extended by the intermediate stop member 84 and the bar 12 bearing against the stop 28 of the slide 29, the narrowing parts mounted upon these bars are laterally shifted in unison to the right or to the left only for the distance of one or two needles.

In Fig. 2 the position of the individual parts of the narrowing device is shown which, for instance during knitting of the sole portion, is necessary to obtain a split connection free of objections in the space between the narrowing combs. From their initial position shown in Fig. 1, the lateral parts 15 and 18 of the narrowing device are removed from the middle part 6 by inserting the second intermediate member 46 in the slide 27 and by withdrawing the intermediate member 67 of the slide 29. A split connection free of objections may now be obtained, as this connection is not endangered by tickler needles or narrowing points positioned in the spaces between the parts of the narrowing device. The intermediate stop member 84 is, during this operation, swung into the inoperative position, so that the bar 3 and therefore the middle part 6 of the narrowing device may, for producing patternings, laterally be shifted directly by the stop 26 of the slide 27. The direction of movement of the middle part 6 is controlled by the movement of the lateral part 15 of the narrowing device located at the right hand side.

Fig. 3 shows the position of the individual parts of the narrowing device for instance for the manufacture of the toe portion of a stocking. The

middle part 6 of the narrowing device is swung upwardly into the inoperative position. The two intermediate members 44, 45 of the slide 27 are withdrawn, so that the stop 26 of this slide is 5 shifted to the left. In the slide 29 both the intermediate members 66, 67 are brought in front of the rod 54, so that the stop 28 of the slide 29 is shifted to the right. Hereby the lateral parts 15 and 18 of the narrowing device are shifted against 10 each other in such a manner, that a space of several needles only remains between them which is necessary for carrying out the narrowing operations.

The rods 42 and 64 are moved in Figs. 2 and 3 15 in opposite directions, indicated by arrows in full and dotted lines for widening and narrowing respectively.

What I claim is:

1. A straight knitting machine having a Jacquard petinet attachment, comprising a three-part narrowing comb extending all over the width of the fabric to be knitted on the machine, a rotatably and shiftably arranged bar, a middle part of said narrowing comb carried by said bar, 20 a spring drawing said bar against a fixed stop, two other bars, one for each lateral part of said narrowing comb, an adjustable stop for each of the bars carrying said lateral parts of the narrowing comb, and a tension spring between each 25 of the last mentioned bars and the said adjustable stops.

2. A straight knitting machine having a Jacquard petinet attachment, comprising a three-part narrowing comb extending all over the 35 width of the fabric to be knitted on the machine, a rotatably and shiftably arranged bar, a middle part of said narrowing comb carried by said bar, a spring drawing said bar against a fixed stop, two other bars, one for each lateral part of said 40 narrowing comb, shiftable rods, a slide shiftably arranged upon each of said rods, a stop provided at each of said slides, narrowing slides for cooperation with the corresponding rods, steps at the upper end of each of said narrowing slides, 45 shiftable stepped cams for raising the corresponding narrowing slides, springs drawing said slides against the corresponding narrowing slides, and a pair of intermediate members located in each of said slides and adapted to be moved in a direction vertically to the longitudinal axis of said 50 rods and to be selectively brought in front of the corresponding rods.

3. A straight knitting machine having a Jacquard petinet attachment, comprising a three-

part narrowing comb extending all over the width of the fabric to be knitted on the machine, a rotatably and shiftably arranged bar, a middle part of said narrowing comb carried by said bar, a spring drawing said bar against a fixed stop, 5 two other bars, one for each lateral part of said narrowing comb, fixed bearings, shiftable rods guided in said bearings, a slide shiftably arranged upon each of said rods, a stop provided at each of said slides cooperating with the rod associated to the corresponding lateral part of the narrowing comb, narrowing slides, one for cooperation with each of said rods carrying said slides, steps at the upper end of each of said narrowing slides, shiftable stepped cams, one for 10 each of said narrowing slides adapted to adjust said narrowing slides in different positions of height, springs, one for each of said slides adapted to draw the latter against the corresponding narrowing slide, a pair of intermediate members 15 in each of said slides adapted to be shifted in a direction vertically to the longitudinal axis of the rods carrying said slides, a handle connected to each of said intermediate members guided in the corresponding slide, and springs each surrounding a pin connecting said handle to the corresponding intermediate member, said springs being located in recesses of the slides and bearing against the bottom of the corresponding recess 20 and the handle respectively.

4. A straight knitting machine having a Jacquard petinet attachment, comprising a three-part narrowing comb normally extending over the entire width of the fabric to be knitted on the machine, a rotatably and shiftably arranged bar, 35 the middle part of said narrowing comb being carried by said bar, a fixed stop, a spring drawing said bar against said fixed stop, a bracket fixed to one end of said bar, a bolt having oppositely arranged flat surfaces mounted in the free end of said bracket, an intermediate stop member swingably supported by said bolt, a pin arranged in a longitudinal recess provided in said intermediate stop member, a spring surrounding said pin for normally retaining the latter against said bolt whereby said pin may alternately engage the flat surfaces of said bolt, two other bars, one for each lateral part of said narrowing comb, an adjustable stop for each of the bars carrying said lateral parts of the narrowing 40 comb, and a tension spring between each of the last mentioned bars and the said adjustable stops.

WOLDEMAR HEINITZ.
